UNITED STATES PATENT OFFICE

112,459

DESIGN FOR A DRESS

Benjamin Fried, New York, N. Y.

Application September 8, 1938, Serial No. 79,786

Term of patent 3½ years

To all whom it may concern:

Be it known that I, Benjamin Fried, a citizen of the United States and a resident of the city of New York, in the county of New York and State of New York, have invented a new, original, and ornamental Design for a Dress, of which the following is a specification, reference being had to the accompanying drawing, constituting a part thereof.

Fig. 1 is a front view of a dress showing my new design.

Fig. 2 is a rear view of the dress shown in Fig. 1.

The characteristic feature of my design resides in the combination on the dress disclosed of the specific halter straps which continue around the sides and back of the bodice to form a border, and the specific girdle below the patch shirring on the bodice, in association with a flared, border trimmed skirt, and a bow trimmed rear waistline, as shown.

I claim:

The ornamental design for a dress, substantially as shown and described.

BENJAMIN FRIED.
